US00D998155S

(12) **United States Design Patent** (10) Patent No.: **US D998,155 S**
Ahearn et al. (45) Date of Patent: ** Sep. 5, 2023

(54) **PROTECTIVE VACUUM SHIELD**

(71) Applicants: **David J. Ahearn**, Little Compton, RI (US); **Edward Carey**, Westport, MA (US); **Walter Bezanuk**, Berkley, MA (US)

(72) Inventors: **David J. Ahearn**, Little Compton, RI (US); **Edward Carey**, Westport, MA (US); **Walter Bezanuk**, Berkley, MA (US)

(**) Term: **15 Years**

(21) Appl. No.: **29/807,596**

(22) Filed: **Sep. 13, 2021**

Related U.S. Application Data

(63) Continuation of application No. 29/737,785, filed on Jun. 11, 2020, now Pat. No. Des. 930,841.

(57) **CLAIM**

The ornamental design for a protective vacuum shield, as shown and described.

DESCRIPTION

FIG. 1 is a perspective view of a protective vacuum shield according to our new design;

FIG. 2 is a top view thereof;

FIG. 3 is a bottom view thereof;

FIG. 4 is a side view thereof;

FIG. 5 is an opposite side view thereof;

FIG. 6 is a front view thereof;

FIG. 7 is a back view thereof;

FIG. 8 is a perspective view of the protective vacuum shield in use; and,

FIG. 9 is another perspective view of the protective vacuum shield for personal service providers in use.

The broken lines in FIGS. 1-9 depict portions of the protective vacuum shield that form no part of the claimed design. Other broken lines shown in FIGS. 8 and 9 depict environmental subject matter and form no part of the claimed design.

1 Claim, 7 Drawing Sheets
